FOLDER FOR CONTAINERS

Robert Rea Brown, Upper Montclair, N. J., assignor to Outserts, Incorporated, New York, N. Y., a corporation of New York

Application August 25, 1936, Serial No. 97,735

7 Claims. (Cl. 40—7)

This invention relates to a device that is to be attached to containers, such as cans, boxes, bottles, jars and the like, in such a way that the device will be retained in position on the cans, bottles, etc. as long as is desired, but can be readily detached therefrom or opened without dismembering or rupturing the device or materially injuring it. The device is made of flexible material, such as paper for example, upon which 10 recipes, pictures or printed matter, of any suitable or desirable sort, may be placed for lending attractiveness of appearance to the device, as well as for the purpose of giving information to the purchasers concerning the contents of the 15 containers.

The device may be made of a continuous strip of flexible material folded into the desired number of sheets or leaves which may, if desired, be of the same size and shape. After the flexible 20 material is folded and attached to the container, access may be gained to the interior of the folder without detaching it and the folder can be again folded and kept in folded position and this operation can be repeated indefinitely. This is 25 especially advantageous where only a portion of the contents of the container is used at one time and it is desirable to keep the folder attached to the container to avoid the danger of the same becoming lost or misplaced.

30 The device is provided with a flap or fold at one end of the strip which may be of any convenient length up to the size of one of the sheets or leaves. This flap may keep the sheets in folded position with the outer surface of this flap 35 and a portion of the outer surface of one of the sheets constituting the surfaces that lie next to a surface of the container. Adhesive attaches to the container a portion of the sheet that lies next to it, and, in a modification of the invention, 40 adhesive also attaches a portion of the flap to the container. The device can be removed from the container without rupturing the device. When the adhesive does not attach the flap to the container, the device may be opened and 45 closed without removing it from the container.

The invention will be understood from the description in connection with the accompanying drawing, in which Fig. 1 is an illustrative embodiment of the invention with the folder partially opened; Fig. 2 is a similar view with the folder closed and adhered to a container shown broken away; Fig. 3 is a view similar to Fig. 1 showing a slight modification; Fig. 4 is a view similar to Fig. 2 showing another modification; 55 Fig. 5 is a back view of the folder shown in Fig. 4;

Fig. 6 is similar to Fig. 4, showing the folder partly open; Fig. 7 is a view similar to Fig. 2, showing another modification; Fig. 8 is a front view of the folder shown in Fig. 7; and Fig. 9 is a view similar to Fig. 7 showing the folder partly 5 open.

In Fig. 1 of the drawing, reference character 1 indicates a strip of flexible material, which may be made of paper or other material that can be folded, and upon the surfaces of which printed 10 matter may be placed. The strip 1 is folded into a number of sheets or leaves 2, 3, 4, that may be the same size or approximately the same size. The number of leaves or sheets 4 is varied in accordance with the need for extent of surface 15 for the printed matter. A short fold or flap 5 is provided at the free end of the sheet or leaf 2 and an adhesive 6, such as glue for example, is provided on the back of the sheet or leaf 3, so that it can be adhered or stuck to the outside surface of a bottle or other container 7, as shown broken away in Fig. 2. The adhesive 6 may be a spot at the middle of the sheet 3 or it may be a streak of adhesive extending partially or entirely across this sheet perpendicular to its edges. 25

The modification shown in Fig. 3 is similar to that just described and the parts are indicated by the same reference characters with primes, the number of sheets in Fig. 3 differing from those in Fig. 1 and also being shown in a different position preparatory to closing the folder. As is obvious from Figs. 2 and 3, the folder is closed by pushing the flap or fold 5 or 5' under the back side of the right hand edge of sheet 3 or 3' whereupon the folder is held in place in folded 35 position but can be opened and closed whenever desired, simply by pulling out the flap 5 or 5' and then closing the same as already described. 25

The flap may be longer or extend farther along the back side of the second sheet and its edge 40 may be glued to the container, as shown in Fig. 4, or it may be extended even farther and be as large as one of the sheets, as shown in Fig. 9, with a hole in it or a notch in its edge so that adhesive can attach one of the sheets to the container. 45

In the modification shown in Figs. 4, 5 and 6, the strip of paper or the like is folded, so that a half size sheet or flap 10 is at one end and is bent or folded at 12 to form the next sheet 11 50 which lies on the outside of the folder and is bent or folded at 13 to form the next sheet 14 55 which is in turn bent at its other edge, and so on for the requisite number of sheets that are folded, as shown in Figs. 4 and 6. This folder 55

is adhered to the container 7 or the like by a spot or strip of adhesive 15 that lies partly along the free edge of the half sheet or flap 10 and partly along the adjacent portion of the sheet 14, as shown in Fig. 5. If an adhesive 15 is used that does not harden, but remains permanently sticky, the folder can be opened by pulling the portion 14 loose, as indicated in Fig. 6, and can be closed again when desired. However, when it is desired to remove the folder, this can be done by pulling the portion 10 away also.

In the modification shown in Figs. 7, 8 and 9, the folder is made of a strip having the folds as indicated at 17'. The strip is folded into a number of leaves 18 in such a manner that the first leaf 18' is on one out side when the folder is folded, and the strip 18'' is on the other out side when the folder is folded.

The leaf 18' may be regarded as the flap. It is provided with a small hole 19 at its middle or other location and a spot of adhesive 20 is placed upon the container 7 to which the folder is to be attached in such a position that when the folded folder is pressed against the container 7, some of the adhesive will pass through the hole 19. When the folder is thus pressed against the container in its folded position the adhesive 20, which passes through the opening 19, will adhere to the third leaf and hold the folder in its folded position on the container. A small amount of the adhesive 20 is shown in Fig. 9 as adhering to the third leaf after the folder has been opened. The folder may be entirely removed without rupturing it, as very little, if any, of the adhesive reaches the flap 18'. Or it may be made so that it can be opened and closed repeatedly without removing it or rupturing it by having the glue 20 contact only with the third leaf and providing a slot in the flap 18' from the hole 19 to the end of this flap.

I claim:

1. In combination, a continuous strip folder and a support, said folder including a flap extending between the body of said folder and said support, and adhesive limited to a small area 45 at the back of a sheet of said folder at a substantial distance from its edges attaching said folder to said support so that its back surface lies adjacent said support leaving the remainder of said sheet free from said support, said folder being adapted to be removed from said support as a whole without rupturing or dismembering it, said flap being adapted to hold said folder closed when in position on said support.

2. In combination, a continuous strip folder and a support, said folder including a flap extending between the body of said folder and said support, and adhesive limited to a small area at the back of a sheet of said folder at substantially the center of said folder attaching said folder to said support so that its back surface lies adjacent said support leaving the remainder of said sheet free from said support, said folder being adapted to be removed from said support as

a whole without rupturing or dismembering it, said flap being adapted to hold said folder closed when in position on said support.

3. In combination, a continuous strip folder and a support, said folder including a flap attached to the outside sheet of said folder and extending between the body of said folder and said support, and adhesive limited to a small area at the back of a sheet of said folder at a substantial distance from its edges attaching said folder to said support so that its back surface lies adjacent said support leaving the remainder of said sheet free from said support, said folder being adapted to be removed from said support as a whole without rupturing or dismembering it, said flap being adapted to hold said folder closed when in position on said support.

4. In combination, a continuous strip folder and a support, said folder including a flap integral with the outside sheet of said folder and extending between the body of said folder and said support, and adhesive limited to a small area at the back of a sheet of said folder at a substantial distance from its edges attaching said folder to said support so that its back surface lies adjacent said support leaving the remainder of said sheet free from said support, said folder being adapted to be removed from said support as a whole without rupturing or dismembering it, said flap being adapted to hold said folder closed when in position on said support.

5. In combination, a continuous strip folder and a support, said folder including a flap extending between the body of said folder and said support, and adhesive limited to the end of 35 said flap and to a small area at the back of a sheet of said folder at a substantial distance from its edges attaching said folder to said support so that its back surface lies adjacent said support leaving the remainder of said sheet free from said support, said folder being adapted to be removed from said support as a whole without rupturing or dismembering it, said flap being adapted to hold said folder closed when in position on said support.

6. In combination, a continuous strip folder and a support, said folder including a flap having a hole in it, said flap extending between the body of said folder and said support, and adhesive passing through said hole and attaching said folder to said support, said folder being adapted to be removed from said support without rupturing or dismembering it.

7. In combination, a continuous strip folder and a support, said folder including a flap having a hole in it, said flap extending between the body of said folder and said support, and adhesive passing through said hole and attaching said folder to said support by adhesion to the second sheet of said folder, said folder being adapted to be removed from said support without rupturing or dismembering it.

ROBT. R. BROWN.
